UNITED STATES PATENT OFFICE

SAMUEL PERLA, OF BROOKLYN, NEW YORK

DESIGN FOR A LAMP

Application filed August 23, 1930. Serial No. 36,750. Term of patent 7 years.

To all whom it may concern:

Be it known that I, SAMUEL PERLA, a citizen of the United States of America, and a resident of Brooklyn, county of Kings and State of New York, have invented a new, original, and ornamental Design for Lamps, of which the following is a specification, reference being had to the accompanying drawing, forming a part hereof.

Figures 1 and 2 are front and side elevational views of the lamp, which has trans-

lucencies A in the side walls for transmission of light. In order to obviate any question of a proper disclosure, it may be stated that the opposite side and end views of the article are substantially identical with the views shown in the two figures.

I claim:

The ornamental design for a lamp substantially as shown and described.

SAMUEL PERLA.
